UNITED STATES PATENT OFFICE.

JOSEPH W. KRAUSE, OF BROOKLYN, NEW YORK.

STIFF-BOSOMED SHIRT.

Application filed December 29, 1924. Serial No. 758,617.

This invention relates to improvements in stiff-bosomed shirts, and has for its principal object to provide a construction and arrangement of parts which make it possible for such a shirt to be worn without possibility of undesirable bulging of the shirt-bosom.

A further object is to so dispose the means used to hold the shirt bosom in place, that they are invisible on the wearer, while still performing their expected function.

Still another object is to provide a construction accomplishing the results above suggested, in which the shirt-body, the bosom, and the bulge-preventing means are joined together in a novel manner, whereby manufacturing costs may be held to a minimum.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are to be taken as part of this specification, and in which I have shown merely a preferred form of embodiment of invention,

Figure 1 is a perspective view of a dress shirt embodying my invention; and

Figure 2 is a sectional view of the same, with the parts occupying relative positions as when the shirt is worn.

Referring to the numerals on the drawing, there is shown at 3 a shirt body, provided with the usual neckband 4, and sleeves 5. The shirt shown is of the coat type, that is, it is open at the front when put on, and closed by joining the front edges, suitable button-holes 6 being provided for this purpose in which studs 7 may be inserted. The bosom parts of the shirt are indicated at 8, and these are intended to be stiff as compared with the shirt body. I have shown the bosom portions 8 made of two plies of material, and additional stiffness is usually given by starching the bosom parts, while the body part is left unstarched. In the process of manufacture the plies of each bosom part are separated at their inner edges, and the corresponding edges of the shirt body are received between the

edge portions of the plies and held by stitching 9. Also held between the edge portions of the plies, and inwardly of the body (Figure 2) are tabs 10, stitches 9 extending also through these tabs, so that shirt body, bosom parts and tabs are joined together, at the inner edges of the bosom parts, with the tabs inside the shirt when the shirt is worn. Means are provided for connecting the tabs around the body of the wearer, but inside the shirt. In the drawing the connecting means comprise tapes 11, preferably elastic, one end of each tape carrying a button 12 for engagement in a corresponding button-hole 13 provided in each one of the tabs 10, and the other ends of the tapes held in adjustable relation by an adjustment slide or buckle 14.

In use, the tapes are positioned as shown in the drawing, and suitable adjustment made before the shirt is put on. After the shirt is closed the tapes exert a pull on the tabs 10, and so keep the shirt bosom in place against the body of the wearer, despite his bending movements. The tabs are inside the shirt, and hence do not detract from appearances; the tapes engage the body of the wearer and have no effect on any part of the shirt except only as they prevent bulging of the bosom. If the tapes were located outside the shirt, they would move down over the shirt during certain bending movements of the body of the wearer, and when the wearer returned to normal erect position the tapes would ride back to normal position, carrying an extra portion of the shirt bunched above them. This bunching of the shirt above the tapes is uncomfortable and spoils the fit of the wearer's coat. By placing the tapes within the shirt this undesirable bunching is entirely avoided, and the shirt is as free to follow the movements of the wearer's body as though the tapes were not present.

I believe also that the method of stitching the edges of the shirt body, and the tabs, between the edge portions of the bosom plies is an improvement on the score of economy, and convenience of cutting and assembling; apart from the consideration that it enables me to locate the tabs and tapes inside the shirt.

I prefer that the tapes shall be detachable from the tabs, for convenience in laundering; and of course I might use a single tape, permanently secured to one tab, and de-

tachably secured to the other tab. And other modifications will suggest themselves, as for instance snap-fasteners instead of buttons, etc.

5 Inasmuch as many changes could be made in the above construction, and many apparently widely different embodiments of my invention could be made without departing from the scope thereof, it is intended 10 that all matter contained in the above description or shown in the accompanying drawing shall be interpreted as illustrative and not in a limiting sense.

It is also to be understood that the language used in the following claims is intended 15 to cover all the generic and specific features of the invention herein described and all statements of the scope of the invention which, as a matter of language, might be 20 said to fall therebetween.

I claim:

1. A coat style shirt having a body portion and bosom portions, tabs joined to the body and bosom portions at the inner edges of the latter and inside the shirt, and means 25 on the inside of the shirt for connecting the tabs with each other.

2. A coat style shirt having a body portion and bosom portions, tabs joined to the body and bosom portions at the inner edges 30 of the latter and inside the shirt, and means on the inside of the shirt for detachably connecting the tabs with each other.

3. The combination set forth in claim 1, in which the bosom portions are two-ply, 35 and in which the body portion and the tabs are secured between the inner edges of the plies.

In testimony whereof I affix my signature.

JOSEPH W. KRAUSE.
